MILK RECONSTITUTING UNIT

Newton A. Blickman, Pearl River, N.Y., assignor to
S. Blickman, Inc., Weehawken, N.J., a corporation of
New York

Application February 12, 1959, Serial No. 54,580

Term of patent 14 years

(Cl. D23—1)

Figure 1 is a front perspective view of a milk reconstituting unit embodying my new design, and
Figure 2 is a rear perspective view.

I claim:

The ornamental design for a milk reconstituting unit,
substantially as shown.
